T. B. JONES

OPERATING VALVE FOR HYDRAULIC PRESSES

Filed Sept. 28, 1923

UNITED STATES PATENT OFFICE.

THOMAS B. JONES, OF TORONTO, ONTARIO, CANADA.

OPERATING VALVE FOR HYDRAULIC PRESSES.

Application filed September 28, 1923. Serial No. 665,404.

To all whom it may concern:

Be it known that I, THOMAS B. JONES, a subject of the King of Great Britain, and resident of the city of Toronto, county of 5 York, Province of Ontario, in the Dominion of Canada, have invented certain new and useful Improvements in an Operating Valve for Hydraulic Presses, as described in the following specification and illustrated in the 10 accompanying drawings, that form part of the same.

The principal objects of the invention are, to provide a means for automatically vibrating the press plunger following the initial 15 operation, and to devise a simple valve structure which may be easily regulated.

The principal feature of the invention consists in operating the pressure control valve to the press with an intermittent movement by means of a plunger hydraulically operated with a reciprocating action, the hydraulic operation of the plunger being opposed to a resilient medium.

In the drawings, Figure 1 is a longitudinal sectional view of the main press operating valve.

Figure 2 is a longitudinal sectional view of the valve for effecting the vibratory action.

30 In the operation of hydraulic presses it has been the custom to operate the control valve directly by a rotatable handle turning a threaded stem which engages the fluid control valve, lifting it from its seat and allowing the pressure to flow to the ram piston.

In certain classes of work it is desirable to impart a vibratory or hammering action to the ram of the press and it is to accomplish this action automatically that this invention has been devised.

40 In the construction herein shown, the main valve consists of the valve body 1 having the inlet port 2 from the pressure fluid supply controlled by the valve 3, the stem 4 of which extends into the discharge chamber 5.

The plunger 6 operating in the discharge chamber and forming a communicating passage to the exhaust chamber 7 is operated by the plunger 8 which is slidably arranged in 50 the upper end of the valve, said plunger being held upwardly clear of the plunger 6 by an encircling coiled compression spring 9.

55 The automatic controlling member illustrated in Figure 2 is preferably arranged in alignment with the plunger of the valve 1 and comprises a substantially cylindrical

body 10 in which is formed a plunger cylinder 11 at the lower end. This cylinder is closed by a threaded gland 12 having a central cylindrical opening 13 in which the 60 plunger rod 14 is guided. A packing washer 15 encircles the plunger rod at the inner end of the gland.

The plunger rod 14 is formed with a cylindrical enlargement 16 which is a sliding fit 65 in the cylinder 11 and against this enlargement is secured the cupped pump washer 17 which is secured in place by a nut 18 threaded on the plunger.

The plunger rod 14 extends into a cylindrical chamber 19 in the body 10 and is provided with a cupped end 20.

A spiral compression spring 21 engages the cupped end 20 of the plunger rod 14 and this spring at the upper end is engaged by 75 a slidable piston block 22 arranged in the upper end of the chamber 19.

The piston block 22 is threaded axially and in this is adjustably secured a threaded member 23 which is preferably provided at 80 its upper end with a roller contact 24. The roller contact is engaged by a suitable means for pressing the piston block inwardly against the compression spring 21 and the means here shown is in the form of a cam 25 85 mounted upon a pin 26 arranged in fixed relation to the body 10. This cam is operated in a suitable manner, either by a hand lever 27 or it may be controlled by a ratchet mechanism connected with the press. A ratchet 90 device is here shown in the form of a wheel 28 having ratchet teeth 29 which are engaged by a ratchet dog 30 carried on the lever 31 which is pivotally mounted on the pin 26.

95 The plunger cylinder 11 is provided with an opening 32 in the side wall intermediate of its length which is connected with the pressure fluid supply leading to the press from the discharge chamber 5 of the main 100 valve so that the pressure fluid will enter the cylinder 11 and will operate against the piston to force the plunger upwardly against the pressure of the spring 21. This action lifts the operating valve plunger 8 105 and allows the closing of the valve 3 controlling the pressure supply and opens the exhaust from the chamber 5 through the plunger 6. This action releases the pressure in the cylinder 11 against the piston 17 and upon the pressure being thus released the spring 21 reacts and pushes the plunger

downward again opening the main valve 3. This action will continue indefinitely as long as the piston block 22 is held depressed by the cam 25 to create a pressure on the piston 17 through the spring 21, but when this cam is turned back, the pressure exerted by the cam on the member 23 through the spring 21 is released and the operating plunger 8 is then lifted from its seat opening the 10 exhaust.

The upward movement of the operating plunger 8 allows the valve 3 to close thereby cutting off the supply of operating fluid to the piston 17 and causing it to cease operating, the spring pressure from above having been relieved.

The pipe 33 leading to the pressure opening 32 in the cylinder 11 is controlled by a suitable regulating valve, here shown in the 20 form of a simple plug stop valve. By means of this valve the speed of the automatic mechanism may be controlled.

In the operation of the device pressure fluid is continually in the chamber connected 25 with the inlet port. By rotating the cam 25, by means of the hand lever 27, the piston block 22 is depressed and through the spring 21 the plunger rod 14 is operated to move the operating valve plunger of the main valve 30 inwardly. This plunger in turn engages the hollow plunger 6 which moves into contact with the valve stem 4 and moving the valve 3 off its seat, the fluid pressure is allowed to flow to the press.

Concurrently in flowing to the press this 35 pressure flows through the pipe 33 to the cylinder 11 and entering below the cup piston the pressure forces the plunger rod 14 outwardly compressing the spring 21. The outward movement of the plunger 14 also 40 lifts the operating valve plunger from its seat and in so doing allows the pressure valve 3 to close cutting off the supply of operating pressure fluid from the press and allowing 45 the exhaust therefrom to pass back through the exhaust passages of the main valve and of course releases the pressure against the piston of the plunger rod 14. The spring 21 immediately reacts and pushes the plunger 50 rod 14 inwardly again opening the main valve 3 and the operation is repeated.

This alternating checking and releasing 55 of the pressure to the press creates a hammering or vibratory effect which is extremely desirable for certain classes of work and as long as the valve 3 is acted upon by the pressure applied through the spring 21 the vibratory action will continue.

The lever 31 may be suitably connected 60 with the ram of the press so as to move up and down with the action of the ram and the ratchet arrangement described will operate to gradually turn the cam to its position of release.

With such a device the ratchet action may

be set to regulate the number of strokes or vibrations of the press at each operation by simply turning the cam member 25 the desired distance.

The ratchet mechanism herein shown is 70 very simple or it may be replaced by other mechanism which will gradually release the downward pressure on the spring 21.

A device such as described is extremely 75 simple, it can be regulated to suit any desirable condition of pressure and speed and will greatly enhance the operative functions of a hydraulic press.

The pressure of the fluid supply to the press may be regulated very accurately and 80 quickly by the adjustment of the member carrying the roller 23 in the piston block 22 which thus regulates the pressure of the spring 21 and consequently regulates the movement of the main valve 3 from its seat. 85

What I claim as my invention is:

1. In a hydraulic valve, a pressure fluid control valve, a plunger for operating said valve, a resilient plunger operatively engaging said valve operating plunger, and hydraulic means for operating said resilient plunger. 90

2. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, and resilient means opposing the operation of said latter plunger. 100

3. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, and adjustable resilient means opposing the operation of said latter plunger. 105

4. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, resilient means opposing the operation of said plunger, and means adapted to increase or decrease the resistance of said resilient means to the action of the said latter plunger. 115

5. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, resilient means opposing the operation of said latter plunger, a slid able member engaging said 125

resilient means, and means for operating said slideable member to regulate the resistance of said slideable member to the hydraulic movement of said latter plunger.

5 6. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, a spiral compression spring engaging said hydraulic plunger, and an adjustable member engaging the outer end of said spring.

15 7. In a hydraulic valve, a pressure fluid control valve having an operating plunger, a plunger operatively connected with the aforesaid plunger, a cylinder enclosing said latter plunger, means for conducting pressure fluid to said cylinder to operate the plunger therein in one direction, a spiral compression spring engaging said hydraulic plunger, an adjustable member engaging the outer end of said spring, and a cam engaging 25 said adjustable member.

8. In a hydraulic valve, a pressure fluid control valve having a plunger, a plunger operatively connected with the aforesaid plunger, a cylinder enclosing said latter plunger, means for conducting pressure fluid to said cylinder to operate the plunger therein in one direction, a spiral compression spring engaging said hydraulic plunger, an adjustable member engaging the outer 35 end of said spring, means for operating said adjustable member, and means actuated by the press for automatically moving said operating means to gradually reduce the resistance of the spring to the hydraulic movement of said hydraulic plunger.

40 9. In a hydraulic valve, a pressure fluid control valve having an operating plunger, a plunger operatively connected with said main valve, a cylinder enclosing said latter plunger, means for conducting pressure fluid

to said cylinder to operate the plunger therein in one direction, resilient means opposing the operation of said plunger, and means for regulating the flow of the pressure fluid to said cylinder.

50

10. In a valve for hydraulic presses, a pressure fluid control valve having an operating plunger and discharge and exhaust chambers connected with the press, a conduit leading from the discharge chamber, 55 a cylinder connected with said conduit, a piston operating in said cylinder, a plunger connected with said piston and operatively connected with said operating plunger, and resilient means engaging said plunger piston to operate it to open the main valve.

11. In a valve for hydraulic presses, a pressure fluid control valve having an operating plunger and discharge and exhaust chambers connected with the press, a conduit leading from the discharge chamber, 65 a cylinder connected with said conduit, a piston operating in said cylinder, a plunger connected with said piston and with said operating plunger, resilient means engaging 70 said plunger piston to operate it to open the main valve, and a stop valve arranged in said conduit to regulate the flow of the pressure fluid to the plunger cylinder.

12. In a valve for hydraulic presses, a fluid pressure control valve having a reciprocating operating plunger, a cylinder arranged in alignment with said operating plunger, a piston operating in said cylinder and connected with said plunger, a cylindrical chamber in alignment with said cylinder, a coil compression spring arranged within said chamber and engaging the piston of said plunger, a piston block slidably arranged in the outer end of said cylindrical 80 chamber and engaging said spring, a member threaded in said piston block, and means engaging said threaded member for operating said piston block in said chamber.

85 THOMAS B. JONES.
